CLAIM

The ornamental design for a tape forming a toy building block base, as shown and described.

DESCRIPTION

FIG. 1 is a top view of a first embodiment of a tape forming a toy building block base in a flat extended condition;

FIG. 2 is a left view thereof;
FIG. 3 is a front view thereof;
FIG. 4 is a right view thereof;
FIG. 5 is a back view thereof;
FIG. 6 is an enlarged cut-away view of the tape forming a toy building block base taken along line 6-6 of FIG. 1;
FIG. 7 is a bottom view of the tape forming a toy building block base;
FIG. 8 is a front view thereof in a condition partially removing the adhesive cover film;
FIG. 9 is an exploded top perspective view of the tape forming a toy building block base in a flat extended condition with the adhesive cover film partially removed;
FIG. 10 is an enlarged partial view of a portion of FIG. 9;
FIG. 11 is a top perspective view of the tape forming a toy building block base in a flat extended condition with the adhesive cover film partially removed;
FIG. 12 is an enlarged partial view of a portion of FIG. 11;
FIG. 13 is a bottom perspective view of the tape forming a toy building block base in a flat extended condition with the adhesive cover film partially removed;
FIG. 14 is an enlarged partial view of a portion of FIG. 13;
FIG. 15 is a top view of the tape forming a toy building block base in a cylindrically rolled condition;
FIG. 16 is a left view thereof;
FIG. 17 is a front view thereof;
FIG. 18 is a right view thereof;
FIG. 19 is a back view thereof;
FIG. 20 is a bottom view thereof;
FIG. 21 is a perspective view thereof;
FIG. 22 is top view of the tape forming a toy building block base in an oblong rolled condition;
FIG. 23 is a left view thereof;
FIG. 24 is a front view thereof;
FIG. 25 is a right view thereof;
FIG. 26 is a back view thereof;
FIG. 27 is a bottom view thereof;
FIG. 28 is a perspective view thereof;
FIG. 29 is a top view of the tape forming a toy building block base in a flat race-track condition;
FIG. 30 is a left view thereof;
FIG. 31 is a front view thereof;
FIG. 32 is a right view thereof;
FIG. 33 is a back view thereof;
FIG. 34 is a bottom view thereof;
FIG. 35 is a perspective view thereof;
FIG. 36 is a top view of the tape forming a toy building block base in a sideways curved condition;
FIG. 37 is a left view thereof;
FIG. 38 is a front view thereof;
FIG. 39 is a right view thereof;
FIG. 40 is a back view thereof;
FIG. 41 is a bottom view thereof;
FIG. 42 is a perspective view thereof;
FIG. 43 is a top view of the tape forming a toy building block base in an up and down curved condition;
FIG. 44 is a left view thereof;
FIG. 45 is a front view thereof;
FIG. 46 is a right view thereof;
FIG. 47 is a back view thereof;
FIG. 48 is a bottom view thereof; and
FIG. 49 is a perspective view thereof.
FIG. 50 is a top view of a second embodiment of a tape forming a toy building block base in a flat extended condition;
FIG. 51 is a left view thereof;
FIG. 52 is a front view thereof;
FIG. 53 is a right view thereof;
FIG. 54 is a back view thereof;
FIG. 55 is an enlarged cut-away view of the tape forming a toy building block base taken along line 55-55 of FIG. 50;
FIG. 56 is a bottom view of the tape forming a toy building block base;
FIG. 57 is a front view thereof in a condition partially removing the adhesive cover film;
FIG. 58 is an exploded top perspective view of the tape forming a toy building block base in a flat extended condition with the adhesive cover film partially removed;
FIG. 59 is an enlarged partial view of a portion of FIG. 58;
FIG. 60 is a top perspective view of the tape forming a toy building block base in a flat extended condition with the adhesive cover film partially removed;
FIG. 61 is an enlarged partial view of a portion of FIG. 60;
FIG. 62 is a bottom perspective view of the tape forming a toy building block base in a flat extended condition with the adhesive cover film partially removed;
FIG. 63 is an enlarged partial view of a portion of FIG. 62;
FIG. 64 is a top view of the tape forming a toy building block base in a cylindrically rolled condition;
FIG. 65 is a left view thereof;
FIG. 66 is a front view thereof;
FIG. 67 is a right view thereof;
FIG. 68 is a back view thereof;
FIG. 69 is a bottom view thereof;
FIG. 70 is a perspective view thereof;
FIG. 71 is top view of the tape forming a toy building block base in an oblong rolled condition;
FIG. 72 is a left view thereof;
FIG. 73 is a front view thereof;
FIG. 74 is a right view thereof;
FIG. 75 is a back view thereof;
FIG. 76 is a bottom view thereof;
FIG. 77 is a perspective view thereof;
FIG. 78 is a top view of the tape forming a toy building block base in a flat race-track condition;
FIG. 79 is a left view thereof;
FIG. 80 is a front view thereof;
FIG. 81 is a right view thereof;
FIG. 82 is a back view thereof;
FIG. 83 is a bottom view thereof;
FIG. 84 is a perspective view thereof;
FIG. 85 is a top view of the tape forming a toy building block base in a sideways curved condition;
FIG. 86 is a left view thereof;
FIG. 87 is a front view thereof;
FIG. 88 is a right view thereof;
FIG. 89 is a back view thereof;
FIG. 90 is a bottom view thereof;
FIG. 91 is a perspective view thereof;
FIG. 92 is a top view of the tape forming a toy building block base in an up and down curved condition;
FIG. 93 is a left view thereof;
FIG. 94 is a front view thereof;
FIG. 95 is a right view thereof;
FIG. 96 is a back view thereof;
FIG. 97 is a bottom view thereof; and,
FIG. 98 is a perspective view thereof.
The Figures depict the tape forming a toy building block base in a variety of conditions to which it may be positioned.

Figures that have been shown separated and bound by bracket are disclosed as such for the ease and clarity of illustration.

The broken lines in FIGS. 10, 12, 14, 59, 61 & 63 enclose portions of the claimed design that are illustrated in enlargements and form no part of the claimed design.
